2,218,703

FLOOR SANDING MACHINE

Arthur N. Emmons, Nedrow, N. Y., assignor to The
Porter-Cable Machine Company Inc., Syracuse,
N. Y., a corporation of New York

Application November 29, 1938, Serial No. 242,977

6 Claims. (Cl. 51—176)

This invention relates to improvements in floor sanding machines of the type disclosed in my copending application, Serial Number 104,496, filed October 7, 1936, which has become Patent No. 2,148,061.

The invention has as an object a particularly simple and efficient construction for yieldingly supporting the sanding drum on the frame and which is conveniently operable to effect leveling of the drum to the surface being finished.

The invention has as a further object a particularly simple mechanism for adjusting the pressure of the sanding drum on the floor, and which mechanism is quickly and conveniently adjusted.

The invention has as a further object means for detachably securing the motor to the frame, and by which the motor can be attached to the frame in a particular convenient manner.

The invention consists in the novel features and in the combinations and constructions hereinafter set forth and claimed.

In describing this invention, reference is had to the accompanying drawings in which like characters designate corresponding parts in all the views.

Figure 1 is a side elevational view of a machine embodying my invention with parts broken away and parts in section.

Figure 2 is a sectional view of the sanding drum with the supporting mechanism therefor shown partly in section and partly in elevation.

Figure 3 is a fragmentary detail sectional view of the mechanism for detachably securing the motor to the frame of the machine.

Figure 4 is a fragmentary side elevational view of the motor casing.

Figure 5 is a detail view of the mechanism for adjusting the pressure of the sanding drum on the floor.

The machine here shown is similar in general form and arrangement to the machine disclosed in my above-mentioned copending application, Serial Number 104,496.

The machine consists of a chassis 10 provided at its forward end with a pair of spaced apart rollers 11, and at its rear end with a swivel caster 12. The rollers 11 and caster 12 movably support the machine on the floor or surface being finished.

The machine further includes a frame 13 pivotally mounted to the chassis on a transversely extending axis 14. The sanding drum 15 is mounted on a shaft 16 journaled in antifriction bearings 17 mounted in the lower ends of arms

18. The arms 18 depend from stems 19 which are slidably mounted in substantially vertically extending apertures in the forward end of the frame, or, as here shown, in the ends of a bracket 20 which is detachably secured to the front or forward end of the frame as by a screw 21. The upper ends of the stems 19 are threaded to receive adjusting nuts 22, the purpose of which is to effect axial adjustment of the stems 19 and arms 18 to level the drum 15, or to adjust the same so that it is parallel with the rollers 11. This adjustment is not material in extent, but only slight to compensate for any inaccuracies during the manufacture and assembly of the machine. It is also desirable to have some yielding movement between the drum and the frame of the machine, particularly to prevent any vibration of the sanding drum from being transmitted to the entire machine. Heretofore, such vibration was compensated for by spring mechanism inserted between the arms 18 or stems 19 and the bracket or frame of the machine. This spring construction not only added materially to the cost of the machine, but adversely affected the performance of the machine.

As here shown, a washer 24 of rubber composition, or other yieldable material, is arranged on the lower portion of the stems 19 intermediate the arms 18 and the bottom of the bracket 20. The washer 24 is sufficiently compressible to allow for axial adjustment of the stems 19 by nuts 22 to effect leveling of the drum 15 and to absorb any undue vibration created by the drum 15 when in operation.

The bearings 17 are not mounted directly in the arms 18, but are arranged in a yieldable bearing mount consisting of inner and outer annular members 26, 27 between which is interposed an annular member 28 of rubber composition or material similar to that of which the washer 24 is formed. The yielding member 28 is vulcanized or permanently secured to the annular members 26, 27. This yieldable bearing mount also functions to absorb the vibration of the drum 15, and further relieves the bearings 17 from any undue strain because of any slight misalignment of the arms 18.

The rear portion of the chassis 10 is formed with an upwardly extending projection 29 formed with a socket into which the lower end of a handle 30 is secured. The projection 29 is also formed with a rearwardly extending portion 31 which, together with a web 32 formed on the bracket 20, serves as handles for conveniently carrying the machine. A bracket 33 is secured

to one side of the projection 29, and a lever 34 is pivotally secured at one end to the bracket and extends transversely of the projection 29, see Figure 5. The opposite side of the projection 5 is formed with a rack 35 provided with a plurality of teeth engageable by the lever 34 to maintain the same in adjusted position.

A tension spring 36 is connected at one end to the lever 34 intermediate its ends, and at the 10 other end to the frame 13. The handle 30 is provided with lever mechanism for holding the rear end of the frame downwardly and the sanding drum out of engagement with the floor and operable to permit pivotal movement of the frame 15 about the axis 14 to bring the sanding drum into engagement with the floor. This pivotal movement is effected by the tension spring 36 and the pressure exerted by the drum on the floor depends upon the adjustment of the lever 34. The 20 lever mechanism for releasing the frame for pivotal movement is shown in my Patent No. 1,974,136, issued September 18, 1934, the spring mechanism shown therein being omitted. It will be observed that the pressure on the sanding 25 drum may be varied by moving the free end of the lever 34 into engagement with the proper tooth of rack 35.

A motor 40 is mounted upon the top side of the frame 13 and is operatively connected to 30 the sanding drum 15 by belt 41. A suction fan is arranged in the rear portion of the casing and is driven by the motor through belt 42. The motor is pivotally mounted at one side to the frame and is provided at the opposite side 35 with a screw 43 for adjusting the motor about its pivot toward and from the frame to effect the proper tension on the belts 41, 42.

An important feature of this invention has to do with the means for detachably and pivotally 40 mounting the motor on the frame. In the machine disclosed in my heretofore mentioned co-pending application, Serial Number 104,496, the frame was provided with spaced apart bosses having an aperture to receive a pivot pin which extended through the motor casing at the rear side thereof.

Floor finishing machines of the type herein referred to are of necessity moved from job to job, and in order that the machine may be conveniently handled it is necessary to remove the 50 motor 40 which is of considerable weight. The pivot structure disclosed in my application referred to afforded a convenient means of removing and mounting the motor on the machine. 55 However, some difficulty was experienced in aligning the aperture in the motor casing with the apertures in the bosses on the frame in order to permit insertion of the pivot pin. With the construction hereinafter described, it is only necessary to set the motor on the frame and move the pivot pins inwardly, the construction embodying means for supporting the motor with the apertures in the motor casing arranged in alignment with the pivot pins.

60 As here shown, the frame 13 is provided adjacent the rear top portion thereof with upwardly extending spaced apart bosses 44 to receive the motor casing therebetween. Pivot pins 45 are mounted in the bosses 44 so as to have axial movement inwardly and outwardly toward each other. As shown in Figure 3, the pins 45 are slidably mounted in the bosses 44 and are formed with keyways 46 of predetermined length. The bosses 44 are provided with screws 47 having a 70 reduced end portion arranged in the keyways 46.

Accordingly, the outward axial movement of the pins 45 are limited, and the arrangement is such that when the pins are moved outwardly the inner ends of the pins project inwardly from the confronting sides of the bosses 44. The sides of the motor casing 40 are provided with inwardly extending apertures 48 to receive the inner ends of the pins 46, and the motor casing adjacent the apertures 48 is provided with an inverted crotch formation cooperable with the inwardly 10 extending ends of the pins 45 to support the motor with the apertures 48 in register with the pins 45, whereby the pins can be moved inwardly to pivotally secure the motor to the frame.

As here shown, the motor casing is provided 15 with inserts 50 secured to the motor casing as by screws 51. The inserts 50 are formed with cylindrical portions 52 extending into the apertures 48, and the outer side of the inserts is of inverted U shape formation with the sides 53 20 diverging downwardly, see Figure 4, and with the apex or intermediate portion arranged in alignment with the upper side of the aperture formed in the insert. Accordingly, when the pins 45 are moved outwardly, the inner ends of the pins clear 25 the cylindrical aperture in the inserts 50, and the motor is then supported by the outer crotch or U formation of the insert. The motor can be then removed from the frame by simply lifting the motor off the frame. The motor is replaced 30 on the frame by placing the crotch formation over the inner ends of the pins which, as before stated, project a slight distance inwardly from the confronting sides of the bosses 44, and it is then only necessary to push each of the pins 46 35 inwardly. If desired, the pins may be secured in the in position by tightening the screws 47.

The sides of the motor casing adjacent the apertures 48 may be formed with the crotch structure integral with the casing. However, the 40 chassis, frame, motor casing, and similar parts of the machine, are preferably formed of aluminum and due to the inherent softness of this metal, the inserts 50 are formed of iron or steel. It will be apparent with this construction that 45 the difficulty of alining the aperture in the casing of a heavy motor with the apertures in the bosses is eliminated.

What I claim is:

1. A sanding machine comprising a frame, a 50 sanding drum journaled on the forward end of the frame, a motor carried by the frame for operating said drum, means for detachably securing the motor to the frame including a pair of pins carried by the frame and arranged in 55 spaced apart relation to receive the casing of the motor therebetween and being movable axially toward and from each other, said motor casing being provided with inwardly extending apertures to receive the ends of said respective 60 pins upon axial movement of the same, and said casing having means adjacent each aperture for guiding and centering said apertures with said pins.

2. A sanding machine comprising a frame, a 65 sanding drum journaled on the forward end of the frame, a motor carried by the frame for operating said drum, means for detachably securing the motor to the frame including a pair of pins carried by the frame and arranged in 70 spaced apart relation to receive the casing of the motor therebetween and being movable axially inwardly and outwardly from each other, means for limiting the outward movement of said pins, said motor casing being provided with in- 75

wardly extending apertures to receive the ends of said respective pins upon inward axial movement of the same, and said casing having means adjacent each aperture and cooperable with the ends of said pins when in out position for guiding and centering said aperture with said pins.

5. A sanding machine comprising a frame, a sanding drum journalled on the forward end of the frame, a motor carried by the frame for operating said drum, means for detachably securing the motor to the frame including a pair of pins carried by the frame and arranged in spaced apart relation to receive the casing of the motor therebetween and being movable axially inwardly and outwardly from each other, said casing being provided with inwardly extending apertures to receive the ends of said respective pins upon inward axial movement of the same, and said casing having means adjacent each of said apertures for supporting the motor casing in spaced apart relation from the frame and alining said apertures with said pins.

4. A sanding machine comprising a frame, a sanding drum journalled on the forward end of the frame, a motor carried by the frame for operating said drum, means for detachably securing the motor to the frame including a pair of bosses carried by the frame and arranged in spaced apart relation to receive the casing of the motor therebetween, a pin mounted in each of said bosses and being movable axially inwardly and outwardly from each other, said motor casing being provided with inwardly extending apertures to receive the ends of said respective pins upon inward axial movement of the same, means operable to limit outward movement of said pins with the inner ends of the same extending inwardly from the confronting sides of said bosses, said motor casing being provided with a crotch formation arranged to engage the inner ends of the respective pins when in out position and support the motor casing with the apertures therein arranged in alinement with said pins.

5. A sanding machine comprising a chassis provided with rollers for movably supporting the same on the surface being finished, said chassis being provided with a projection extending upwardly from the rear end thereof, and a handle mounted in said projection for manipulating the machine, a frame pivotally mounted intermediate its ends to said chassis, a sanding drum journalled in the forward end of the frame, a motor carried by the frame and motion transmitting means operatively connecting said motor and drum, a lever pivotally mounted at one end to said projection and extending transversely of the frame, said projection being provided with a rack having a plurality of teeth, said lever being adjustable about its pivot and the intermediate portion of said lever engaging any selected one of said teeth to maintain the lever in adjusted position, a tension spring secured at one end to the lever intermediate its ends, and the opposite end being secured to the rear portion of said frame and being operable to urge said frame about its pivot to move the sanding drum into engagement with the surface being finished.

6. A sanding machine comprising a chassis provided with rollers for movably supporting the same on the surface being finished, a sanding drum support pivotally mounted on said chassis, a sanding drum journalled in said support and means for effecting rotation of said drum, a projection extending upwardly from the rear end of said chassis, a lever pivotally mounted to said projection and extending horizontally, said projection being provided with a rack having a plurality of teeth, said lever being adjustable about its pivot and engaging any selected one of said teeth to maintain the lever in adjusted position, a tension spring secured at one end to said lever and at the opposite end to said sanding drum support and being operable to urge said support about its pivot to move the sanding drum into engagement with the surface being finished.

ARTHUR N. EMMONS.
